UNITED STATES PATENT OFFICE.

GEORGE K. PUTNAM, OF MONTPELIER, VERMONT.

BOOK-REST.

SPECIFICATION forming part of Letters Patent No. 593,120, dated November 2, 1897.

Application filed February 1, 1897. Serial No. 621,508. (No model.)

To all whom it may concern:

Be it known that I, GEORGE K. PUTNAM, of Montpelier, in the county of Washington and State of Vermont, have invented a new and 5 Improved Book-Rest, of which the following is a full, clear, and exact description.

The purpose of this invention is to provide a superior device for holding account-books on tables or desks the surfaces of which are 10 either flat or inclined.

The invention will be fully described hereinafter and defined in the claims.

Reference is to be had to the accompanying drawings, forming a part of this specification, 15 in which similar characters of reference indicate corresponding parts in all the figures.

Figure 1 is a perspective view of my invention. Fig. 2 is an end elevation thereof. Fig. 3 is a detail section on the line III III of 20 Fig. 1. Fig. 4 is a fragmentary sectional view showing a detail hereinafter described, and Fig. 5 is a section on the line V V of Fig. 4.

The book-rest comprises a rigid main portion and two sliding side portions. The main 25 portion is constructed of four longitudinal plates 4, joined to each other at their front ends by a plate 5 and at their rear ends by a plate 6. The rear ends of the plates 4 are considerably wider than the forward ends of 30 the plates, so that the plane upper edges of the plates will be held inclined forwardly when rested on a horizontal surface. The rear end plate 6 is of a width equal to the greatest width of the plates 4 and has at its lower edge 35 a plate 7, adapted to rest on the surface supporting the device and secured to the lower rear edges of the plates 4 as well as to the plates 6, so as to strengthen the whole structure.

40 Formed in the two outer of the plates 4 are orifices 8, which are two for each outer plate 4 and respectively carry the bars 9. The bars 9 are connected in pairs by the two plates 10, which are respectively attached to 45 the outer ends of the pairs of bars and have a form similar to the form of the plates 4, the front end of each plate 10 having an upwardly-extending lug 11, registering with the upper edge of the plate 5, which upper edge is projected above the plane upper edges of the

plates 4 to form a ledge against which the book may bear. By moving the plates 10 in and out the width of the rest may be regulated and books of various sizes held. The two inner of the four plates 4 are each provided with two orifices 12, the widths of which are approximately twice the width of the openings 8. The forward opening 12 in each plate 4 is adapted to receive each end of the forward bars 9, so as to hold the bars from 55 lateral displacement. The rearward opening 12 in the plate 4 is adapted to receive both ends of the rearward bars 9 and hold said bars, as before explained.

As shown in Figs. 4 and 5, bars 9 of each 60 pair, the members of which pairs are engaged with each other, are provided in their engaging edges with dovetail grooves 13. The inner end of each bar 9 has secured in the groove 13 thereof a double dovetail plate 20, 65 one dovetail portion of each plate 20 fitting within the groove 13 of the bar which carries said plate and the second dovetail portion of each plate 20 fitting slidably within the groove 13 of that bar 9 which is engaged with 70 the bar 9, which carries the said plate 20. By this construction the plates 10 may be moved inward against the outer plates 4, or may be moved outward until the inner ends of the bars 9 in each pair of interengaged bars are 75 adjacent to each other, whereupon the plates 19 of the respective pairs engage each other and prevent further outward movement of the plates 10.

A hand-supporting plate 14 is provided at 80 its lower rear edge with a triangular cleat 15, with which the metal plates 16 are connected. These plates are bent to form hooks engaged with the upper edge of the plate 5. By these means the plate 14 may be adjusted transversely along the bars 5 to suit the convenience of the person using the book-rest. The plate 14 is useful when the writer has reached the lower portion of the pages.

The plate 6 is provided at its rear side with 85 a standard 17, the upper end of which is concaved to receive the back of the book and support the book in a very much inclined position should this be desired. The standard 17 is pivoted on a bolt 18 and bears against the pin 90 100

19, so that the standard may be moved to lie horizontal with the plate 6 or to extend vertically therefrom, in which latter position the standard will engage with the pin 19 and be 5 supported thereby.

The invention is useful on desks having either horizontal or inclined surfaces, and by placing the book open on the rest the book will be held convenient for the person using 10 it. If it is desired to simply read from the book, the book may be raised on the standard 17. By pushing the plates 10 inward and moving the standard 17 to a horizontal position, the rest may be folded to a very compact form and carried easily about. 15

A U-shaped bar 21 is pivoted at its ends to the two inner of the four plates 4 and is capable of swinging upward to engage the two forward of the bars 9, so as to be supported 20 vertically, as shown in Fig. 1. The bar 21 may also swing forwardly and downwardly to lie below the upper edges of the plates 4, in which position the bar is inactive. The purpose of the bar 21 is to support the rear portion 25 of a book which is too short to extend between the plate 5 and the standard 17, in which case the front edge of the book rests on the plate 5 and the rear portion is supported by the bar 21.

Having thus fully described my invention, 30 I claim as new and desire to secure by Letters Patent—

1. A book-rest having a stationary frame portion provided with four longitudinal plates joined at their front and rear ends by transverse plates, the forward of the transverse plates having its upper edge extending above the longitudinal plates to form a ledge against which the book may bear, two plates 35 respectively at the side of the stationary frame portion and means for slidably mounting said side plates so that they may move toward and from the stationary frame portion, the front end of each side plate having an upwardly- 40

extending lug matching with the forward transverse plate, substantially as described.

2. A book-rest having a stationary frame portion provided with longitudinally-extending plates joined by transverse plates at their front and rear ends, two pairs of parallel bars 50 sliding transversely in the longitudinal frame-plates, the bars passing through individual openings in the outer of the longitudinal plates, and the pairs of bars respectively passing through joint openings in the inner of the longitudinal bars, a plate carried by each bar to limit the outward movement thereof, and a side plate secured to one bar of each pair and slideable with the bars toward and from the stationary frame portion, substantially as described.

3. The combination with a support, of two plates arranged with adjacent edges and the plates being in the same plane with each other, each plate having a groove formed in the edge adjacent to the companion plate, and each plate carrying a rigid projection, the projection of each plate being slideable within the groove of the companion plate and the projections being capable of engagement 65 with each other to prevent the separation of the plates.

4. A book-rest having a frame with longitudinal plates joined to each other at their front and rear ends by transverse plates, the forward of the transverse plates having its upper edge located above the longitudinal plate to form a ledge for supporting the book, two plates slideable transversely in the longitudinal plates of the frame, and a side plate carried at the outer end of each of the sliding plates, the forward ends of the side plates being upturned to coact with the upper edge of the front transverse plate.

GEORGE K. PUTNAM.
